UNITED STATES PATENT OFFICE.

WILLIAM R. FARNSWORTH, OF TURNER'S FALLS, MASSACHUSETTS, ASSIGNOR
OF ONE-HALF TO THE CLARK MACHINE COMPANY, OF SAME PLACE.

PAPER-WINDING MACHINE.

SPECIFICATION forming part of Letters Patent No. 535,326, dated March 5, 1895.

Application filed December 19, 1894. Serial No. 532,302. (No model.)

To all whom it may concern:

Be it known that I, WILLIAM R. FARN-
WORTH, a citizen of the United States, resid-
ing at Turner's Falls, in the county of Frank-
lin and State of Massachusetts, have invented
5 new and useful Improvements in Paper-Wind-
ing Machines, of which the following is a speci-
fication.

The object of this invention is to improve
10 the construction of paper winding machines
to the ends of increased efficiency and even-
ness in the winding operation, and of render-
ing the winding machine of unusual conven-
ience and availability for the mounting there-
15 in, and removal therefrom, of the winding
arbor with the fully or partially wound roll
of paper, or for the placing of the winding
roll out of pressure contact with the pressure
roll to permit the splicing of the ends of pa-
20 per or for other purpose.

The invention consists in combinations of
devices, and in the constructions of certain of
the devices, all substantially as will herein-
after fully appear and be set forth in the
25 claims.

Reference is to be had to the accompanying
drawings, in which—

Figure 1 is a side elevation of my improved
30 paper-winding machine. Fig. 2 is an oppo-
site side elevation of part of the machine.
Fig. 3 is a plan view. Fig. 4 is a vertical sec-
tional view through one of the slide-supports
35 for the separable journal-bearing for the wind-
ing roll, which involves novelties of construc-
tion to be hereinafter more particularly re-
ferred to. Fig. 5 is a perspective view of a
double form of the improved paper-winding
40 machine.

Similar characters of reference indicate cor-
45 responding parts in all the views.

The machine of this invention comprises
suitable framing and supports, and as shown,
has the side standards, A, cross-braced or tied,
and has as a part or fixture thereof the oppos-
45 ing uprights, A², the upper edges, a, of both
being similarly oblique and provided with
dove-tail ribs, 10, on which are movably fitted
the slides, b, on which are mounted the jour-
nals for the paper-winding roll, B.

50 The roll, C, which is mounted in the fixed
journal boxes, c, at the top of the frame, is

the pressure drum, its axis of rotation being
invariable.

The winding roll is so mounted on the slides
therefor that as the diameter thereof increases 55
as the winding-on of paper progresses, the axis
of the winding-roll will automatically recede
from the pressure drum while the roll of pa-
per making thereon is always circumfer-
entially in pressure bearing against the press- 60
ure drum.

The slide, b, has the journal-box, d, (for
each end bearing of the arbor of the winding-
roll, B,) connected thereto for a slight swiv-
eling movement whereby the periphery of 65
the roll of paper being made may conform
throughout its entire line of contact to the
pressure drum, whereby any unevenness in
the thickness of the paper which may be found
at either end of the roll, may be compensated 70
for, and as specifically shown,—although de-
partures may be made from such specific
means without departing from the inven-
tion,—each journal box, or block, d, has, de-
pending below its base, the stud, d², which 75
enters a socket, b², therefor in the slide, b.
There is connected with each journal-box car-
rying-slide, b, at each side of the machine, a
sprocket-chain, h, for which are the support-
80 ing and guiding sheaves, i, i, and the sprocket-
wheel, j, said chain having a winding engage-
ment around these wheels. Each chain has
the take-up device, exemplified in the turn-
buckle, e, which is merely for the purpose of 85
having the chain run with proper freedom
and without too much lash as well known in
sprocket-wheel and chain devices. A second
turn-buckle, 30, is comprised in each sprocket-
chain at its connection with the slide, b, so 90
that by letting out or taking up the turn
buckle, 30, at the one side or the other of the
machine, the axis of the winding-roll may be
inclined in a very slight degree from its par-
allelism with the adjacent face of the pressure 95
drum. Each of these journal boxes for the
winding-roll is, as shown in Figs. 1 and 4, con-
structed with upper and lower members, 15
and 16, the upper or cap member being hinge-
connected at 17, to the base member, 15.

The separable journal-box is held closed by 100
the cam-ended handle-lever, f, which is piv-
otally mounted between the duplicated arms,

g, which have their lower ends pivotally connected to the base section, 15, of the journal-box. Thus is provided a convenient means for enabling the removal of a fully wound roll 5 of paper and the mounting in the journal supports therefor of the new winding roll, or arbor, for the roll of paper next to be wound thereupon. By properly swinging the cammed handle-lever, f, at each journal-box, and 10 then swinging such lever on the supporting arms, g, the hinged upper section of the journal-box may be released and unobstructed to be swung open; and the reverse of these operations is only necessary to confine the new 15 winding roll when set in the journal-boxes.

The sprocket wheel is so mounted and applied that the winding roll may have its receding motion away from the pressure-drum, the sprocket and chain connection in no wise 20 interfering with such movement; but there is combined with each sprocket wheel means for imparting thereto, at pleasure, rotational movements whereby the chains, h, may cause the slides, b, to carry the winding roll at any 25 distance from the pressure drum which may be requisite or convenient for any of a number of reasons. This means, as here shown, consists in the ratchet-wheel, k,—fast on the shaft, l, on which the sprocket-wheels, j, j, 30 are also fast,—and the lever, m, loosely hung on said shaft, l, and having the driving pawl, n, which at pleasure may be swung into engagement with the ratchet-wheel, k, so that by a swinging reciprocatory movement of the 35 lever, the journal-supports for the winding-roll may be moved as far as necessary in a direction against the gravitation of the winding-roll and sliding journals therefor.

o is a detent for engaging the second ratchet-wheel k² which is fixed on the shaft l to temporarily hold it and parts with which it is connected from retrograde movement, so long as such shall be desired. Of course it is understood that when the winding machine is 45 being operated for the winding of paper onto the winding roll, the pawl-carrying lever, m, and the detent, o, are in their positions of disengagement, as shown by the full lines in the drawings.

50 Inasmuch as the pressure of the winding-roll and roll of paper thereon against the fixed pressure drum, C, is variable, according to the extent of progression of the winding operation and the correspondingly increased size 55 and weight of the roll of paper, counterpoise devices are applied, the tendency of which is to exert the greatest pressure upon the winding-roll in a direction transversely of its axis, and toward the pressure-drum at the initial 60 part of the winding operation, such pressure gradually decreasing as the size of the roll of paper being wound, increases, so that the paper will be wound equally solid and close from its axis to its circumference, and as an efficient 65 means to this end I have provided on the shaft, l, (preferably at the end opposite the ratchet-wheel, k,) the fusee, or snail-cone, t,

the cord, u, having one end in engagement with one of the larger spiral convolutions of the snail-cone, an elevated guiding sheave, v, 70 over and around which the cord passes, and the counterweight, w, connected to the other end of the cord. This device is so arranged and adjusted that the draft of the weight and cord, w, u, is on one of the larger convolutions 75 of the snail-cone when the axis of the roll of paper is nearest the pressure drum, at which time the weight of the paper-roll is the least.

As the machine is running under usual conditions, the ratchet and sprocket-wheels, k, j, 80 and the chain, h, are free so that as the roll of paper makes, the chain has its progressive movement in the direction of the arrows shown in Figs. 1 and 2, against the stress of the weight, w, through the medium of the chain, 85 as affected by said weight and intermediate connections, the snail-cone also having its rotational movements as indicated by the arrow adjacent thereto, Fig. 2. Thus the farther the winding operation progresses, and the 90 larger and heavier becomes the roll of paper, the cord, u, will become also wound around the smaller convolutions of the snail-cone whereby the action of the weight, w, on the cord, working around the smaller part, will 95 consequently exert lessening power to rotate the shaft, l, and by such lessened force for rotation the draft action of the sprocket-chain, or chains, h, h, in the direction to press the winding-roll against the pressure-drum will 100 be lessened in a ratio more or less nearly corresponding to the increased weight, and the correspondingly increased power for gravitation, of the made-up roll of paper.

In paper-winding machines embodying the 105 features already described, in whole or in part, it is advantageous and desirable to lead the paper down to the winding-roll, from the web or supply, by having it guided over and around an overhead guide-roll, G, which is 110 axially parallel with the winding-roll. This overhead guide-roll, G, may be supported by side uprights of the main framing, A, or by supports otherwise sustained.

In Fig. 5, in which a double winding machine is illustrated, side uprights, H, H, as 115 aforementioned, are shown, on tops of which are constructed slide-ways, or ribs, x, x, for the journal-supports, y, for the guide-roll, G.

A screw, q, is supported in a suitable lug, 120 25, of each support, H, to operate upon the adjacent movable journal-support, y, so that minute adjustments of either, or both, of these supports for the ends of the roll, may be acquired to compensate for any unevenness 125 of the thickness of the paper, which latter sometimes runs slightly thicker at, or near, one edge than at the other.

In Fig. 5, in which the duplex paper-winding machine is illustrated, having the characteristics substantially as hereinbefore described, in duplication, the paper is indicated as coming toward the guide-rollers, G, G, as 130 of double width, the position of a slitter be-

ing indicated at *z*, which severs the paper intermediately and longitudinally one-half running over one guide-roll, *G*, to the forward winding roll, while the other half runs over the other guide-roll to the rear winding-roll. As shown, the rolls, *G*, *G*, are at different heights so that the paper running to the forward roll may have no engagement with the rear guide-roll.

10 Having thus described my invention, what I claim, and desire to secure by Letters Patent, is—

15 1. In a paper-winding machine, the combination with the pressure drum, of a winding-roll, opposite supports having parallel slide-ways, slides movable in said ways and supporting the journals for the winding-roll, and means for causing either one of the journals to have an independently adjusting movement whereby the axis of the winding-roll may, as purposed, be rendered slightly out of parallelism with the pressure-drum, substantially as and for the purpose set forth.

20 2. In a paper-winding machine, the combination with the fixed pressure-drum, of the winding-roll mounted in sliding journals, substantially as described, and having at each end means for compelling both journals to move in unison and means for adjusting the journals, one slightly forward of the other, the guide-roll, *G*, and adjustably mounted journals therefor, substantially as and for the purposes set forth.

25 3. In a paper-winding machine, the combination with a fixed pressure-drum, a winding-roll, a support having slide-ways on which the journals of the winding-roll move, a sprocket-wheel and guiding sheaves at each end of the machine and the sprocket-chains running around said sprocket and guiding wheels and having connections with the journal-supports for the winding-roll, and means for causing the rotational movements to said sprocket-wheels, substantially as described.

30 4. In a paper-winding machine, the combination with a fixed pressure-drum, a winding-roll, a support having slide-ways on which the journals of the winding-roll move, a sprocket-wheel and guiding sheaves at each end of the machine and the sprocket-chains running around said sprocket and guiding wheels and having connections with the journal-supports for the winding-roll, and connections between the two sprocket-wheels whereby they both move in unison, a ratchet-wheel movable as one with one of the sprocket-wheels and a pawl-carrying lever cooperating with said ratchet-wheel, substantially as described.

35 5. In a paper-winding machine, the combination with a fixed pressure-drum, a winding-roll, a support having slide-ways on which the journals of the winding-roll move, a sprocket-wheel and guiding sheaves at each end of the machine and the sprocket-chains running

40 around said sprocket and guiding wheels and having connections with the journal-supports for the winding-roll, and connections between the two sprocket-wheels whereby they both move in unison, a ratchet-wheel movable as one with one of the sprocket-wheels, a pawl-carrying lever cooperating with said ratchet-wheel, and a shiftable detent device which at pleasure may be thrown into engagement with a ratchet-wheel which is movable in unison with one of the sprocket-wheels, substantially as described.

45 6. In a paper-winding machine, the combination with a fixed pressure-drum, a winding-roll, a support having slide-ways on which the journals of the winding-roll move, a sprocket-wheel and guiding sheaves at each end of the machine and the sprocket-chains running around said sprocket and guiding sheaves and having connections with the journal-supports for the winding-roll, and connections between the two sprocket-wheels whereby they both move in unison, means for effecting the rotational movements of said sprocket-wheels and a turn-buckle connecting a part of each sprocket-chain with the journal supports for the winding-roll, substantially as described.

50 7. In a paper-winding machine, the combination with a fixed pressure-drum, of a winding-roll, a support having slide-ways, the slides, *b*, *b*, movable thereon, the journal-boxes for the ends of the winding-roll which are swiveled on said slides the paired sprocket-wheels, guiding-sheaves, and sprocket-chains, and the take-up connections between the chains and slides, substantially as described.

55 8. In a paper-winding machine, the combination with the pressure-drum, of the sliding journals in which is mounted the winding-roll, the shaft, *l*, having the sprocket-wheels thereon, and the suitably guided chains engaging said sprocket-wheels and having connections with said journals, the fusee or snail-cone on said shaft, the cord, *u*, and sheave, *v*, therefor, one end of the cord being connected to the fusee and the other end carrying the weight, all whereby the weight, through the medium of its cord connection with the fusee, imparts a decreasing power for rotation on said shaft, *l*, substantially as and for the purpose set forth.

60 9. In a paper-winding machine, the combination with a fixed pressure drum, of a winding-roll, opposite supports having parallel slide-ways, slides movable in said ways, and journal-boxes for the opposite ends of the winding-roll which are swiveled to said slides, substantially as described and for the purpose set forth.

WILLIAM R. FARNSWORTH.
